CLAIM

The ornamental design for a beauty lamp as shown and described.

DESCRIPTION

FIG. 1 is a top, front and right perspective view of a beauty lamp showing our new design;

FIG. 2 is a front elevational view thereof;

FIG. 3 is a rear elevational view thereof;

FIG. 4 is a right view thereof;

FIG. 5 is a left view thereof;

FIG. 6 is a top plan view thereof;

FIG. 7 is a bottom plan view thereof; and,

FIG. 8 is a bottom, rear and right perspective view, showing the beauty lamp in a folded configuration with a base removed.

The evenly broken lines illustrate portions of the beauty lamp that form no part of the claimed design.

1 Claim, 8 Drawing Sheets
